UNITED STATES PATENT OFFICE.

JOHN A. DE VILBISS, OF ST. LOUIS, MISSOURI, ASSIGNOR, BY MESNE ASSIGNMENTS, TO
DE VILBISS ENDLESS FILM MACHINE COMPANY, A CORPORATION OF MISSOURI.

METHOD FOR HANDLING A FLEXIBLE STRIP.

Application filed June 2, 1919. Serial No. 301,235.

To all whom it may concern:

Be it known that I, JOHN A. DE VILBISS, a citizen of the United States, residing at St. Louis, Missouri, have invented a certain new and useful Improvement in Methods for Handling a Flexible Strip, of which the following is a full, clear, and exact description, such as will enable others skilled in the art to which it appertains to make and use the same.

This invention relates to devices of the character that are used for storing a flat record strip of flexible material that is adapted to be fed from a source of supply, coiled to bring it into a reduced space and held ready for uncoiling and reuse at will.

One object of my invention is to provide a method of handling a strip of flexible material which makes it possible to feed a relatively long, continuous, flat strip off of and onto a rotatable supporting device on which the major portion of the strip is wound to form a source of supply.

Another object is to provide a method of handling a strip of flexible material which makes it possible to draw a flat strip from a source of supply consisting of numerous coils or loops of the strip without gradually diminishing the diameter or circumference of the source of supply, thereby enabling a strip to be fed intermittently a definite distance at each step by means of a feeding mechanism that acts directly on the device that supports the major portion of the strip constituting the source of supply.

Another object is to provide a device for supporting a flexible strip which is so constructed that a flat flexible strip can be wound onto same edgewise and maintained in operative position with the coils or loops of the strip extending parallel to each other and disposed at right angles or substantially so to the surface of the device on which the strip is wound.

And still another object is to provide an efficient apparatus for handling a flat, continuous band or flexible strip of relatively great length that is adapted to be fed continuously or intermittently. Other objects and desirable features of my invention will be hereinafter pointed out.

My method, broadly stated, consists in winding a flat strip of flexible material edgewise onto a rotatable supporting device and maintaining the coils or loops of the

strip in parallel relation to each other in a position at right angles or substantially so to the portion of the device on which the strip is wound. My method can be used successfully for handling strips of various kinds of material and the supporting device that carries the major portion of the strip constituting the source of supply can be formed in numerous ways without departing from the spirit of my invention. I have herein illustrated my method used for handling a flat strip consisting of a film such as is used in moving picture machines, but this is only one of numerous purposes for which my method can be successfully used. Moreover, while I have herein illustrated my method used for handling a continuous strip in the form of an endless band that is fed off of and onto a supporting device simultaneously, it is immaterial, so far as my broad idea is concerned, whether the strip has two ends or is in the form of an endless band. The apparatus herein illustrated for practicing my method is designed for use in moving picture projecting machines for handling a continuous film or picture strip, but the general construction and principle of operation of said apparatus is applicable to devices for supporting various other kinds of flat flexible strips.

Figure 1 of the drawings is a side elevational view of an apparatus constructed in accordance with my invention for handling a relatively long, continuous strip or endless band that is adapted to be fed to or through a mechanism which acts on the strip or with which the strip co-operates.

Figure 2 is a vertical cross sectional view of a portion of the strip carrier, taken on the line 2—2 of Figure 1.

Figure 3 is an enlarged horizontal sectional view, taken on the line 3—3 of Figure 1, illustrating the construction of the spreading device that is combined with the strip guide at the lower side of the strip carrier.

Figure 4 is an enlarged horizontal sectional view of the strip guide, taken on the line 4—4 of Figure 1; and

Figure 5 is an enlarged horizontal sectional view, taken on the line 5—5 of Figure 1, illustrating the guiding device at the upper side of the strip carrier over which the strip passes as it is unwinding from said carrier.

Referring to the drawings which illus-

2
 trate an apparatus that can be used for practicing my method. A designates a flat strip of flexible material in the form of an endless band, and B designates a rotatable supporting device or carrier onto which said strip is wound. Instead of winding the strip A onto the device B flatwise so as to form a number of superimposed coils or loops, as is now the universal method of winding a flat flexible strip onto a supporting device, I wind the strip A onto the device B edgewise so as to form numerous coils or loops that are arranged parallel to each other and which are disposed at right angles or substantially so to the portion of the device B onto which the strip is wound. The particular construction of the strip carrier B is immaterial, but it is essential that said carrier be of sufficient diameter to permit the strip to be wound onto same edgewise without disrupting the strip or stretching it out of shape. In using my method for handling a strip consisting of a film such as is used in moving picture machines, I have found that the film can be successfully wound edgewise onto a rotatable carrier or supporting device provided with a rim portion five or six feet in diameter.

The strip carrier B herein illustrated consists of a wheel rotatably mounted on a horizontally disposed shaft 1 and provided with a flat rim portion 2. The strip A is wound edgewise onto said rim portion 2 so as to form numerous parallel coils or loops that are disposed at right angles or substantially so to the rim portion 2, and means is provided for confining the coils of the strip in operative position on said rim portion. The means herein illustrated for this purpose consists of a side flange 3 on one edge of said rim portion and a ring shaped member 4 surrounding said rim portion and arranged in parallel relation to the side flange 3, said ring shaped member 4 being mounted in such a manner that it can be adjusted laterally towards and away from the side flange 3, so as to adapt the carrier B to strips of different lengths. To wind the strip A onto the carrier B the ring shaped member 4 is first arranged in close proximity to the side flange 3 and the end of the strip is then inserted edgewise between the flange 3 and the member 4 and temporarily attached to said member 4 in any preferred manner. The strip carrier B is then revolved so as to wind the strip edgewise onto the rim portion 2 of the carrier between the two parts 3 and 4 that hold the coils or loops of the strip in parallel relation and at right angles to the rim portion 2. During the operation of winding the strip onto the carrier the ring shaped member 4 is moved laterally away from the side flange 3 so as to increase the space that receives the portion of the strip constituting the source of

supply. Any suitable means can be used for moving the ring shaped member 4 towards and away from the side flange 3, such, for example, as screws 5 adjustably mounted in a flange 3^a or in bearings on the rim 70 portion 2 of the carrier and connected at their inner ends to the ring shaped member 4 in such a manner that when said screws are turned in one direction the member 4 will be moved towards the side flange 3, 75 and when said screws are turned in the opposite direction, said member 4 will be moved away from the side flange 3.

By arranging the strip on the carrier B in this manner I am able to confine a strip 80 of relatively great length in a compact space and can feed or draw the strip from the carrier without gradually diminishing the diameter or circumference of the source of supply. This feature of being able to draw a 85 strip from a source of supply without gradually diminishing the diameter or circumference of the source of supply makes it possible to feed the strip intermittently a definite distance at each step by means of a feeding mechanism that acts directly on the reel, carrier or device that supports the source of supply from which the strip is drawn, a 90 thing that is not possible when a strip is wound flatwise onto a reel or rotatable supporting device, due to the fact that the diameter of the source of supply changes constantly while the strip is being fed, and thus makes it necessary to have the feeding mechanism act directly on the strip. In the 100 apparatus herein shown the feeding mechanism for the strip acts directly on the strip, but I desire to call attention to the above mentioned feature of my method and apparatus, as it is of great importance in handling some kinds of strips. 105

The strip A is herein illustrated as leading forwardly from the carrier B over a guide roller 6, then through the projecting apparatus of a moving picture machine, designated 110 as an entirety by the reference character C, and thence rearwardly from a guide roller 6^a to the strip carrier B. The strip is acted upon by a feeding mechanism 7, and the guide rollers 6 and 6^a over which the strip 115 passes are so disposed that the strip A will be presented in a flat condition to the projecting apparatus through which the strip passes. In the apparatus herein illustrated a stationary guiding device D is arranged 120 in proximity to the strip carrier B so as to twist the strip from a horizontal into a vertical position as it is being rewound onto the carrier, it being understood that the ends of the strip are connected together after the 125 strip has been wound onto the carrier and the strip thereafter detached from the member 4 so as to form a continuous band or belt that leads from the upper side of the strip carrier to or through the means that 130

acts on the strip or with which the strip cooperates, and thence back to the lower side of said carrier. The guiding device D consists of a stationary guideway designed in 5 such a manner that it will cause the strip to twist gradually from a horizontal into a vertical position in traveling through same, and tension rollers 8 combined with said guideway in such a manner that the strip 10 travels between said tension rollers just before the strip passes onto the rim portion 2 of the strip carrier B, said tension rollers operating to keep the strip taut. The front end portion of the guideway D is flared, as 15 shown in Figure 4, but the rear end portion 9 of said guideway is of substantially channel shape in cross section and of approximately the same dimensions as the cross section of the strip, as shown in Figure 2. 20 The channel shaped portion of the guiding device D extends under the rim portion 2 of the strip carrier and is arranged in sufficiently close proximity to the side flange 3 on said rim portion to insure the strip A being 25 fed edgewise onto the rim portion of the carrier and flat against the inner side of the side flange 3 on the carrier. In order to spread the strip away from the side flange 3, and thus form a space for the portion of 30 the strip that is being rewound onto the carrier B, I have provided the stationary guiding device D with a spreading member 10 having a sharp front end which is disposed in sufficiently close proximity to the 35 inner side of the flange 3 on the carrier B to force the strip laterally away from said flange, as shown in Figure 3, and thus provide a space for the portion of the strip that passes from the channel shaped part 9 of 40 the guiding device D onto the strip carrier. The rim portion 2 of the carrier onto which the strip is wound edgewise is preferably of greatest diameter adjacent the side flange 3 or is tapered slightly or made slightly cone 45 shaped, as shown in Figure 2, so as to cause the coils or loops of the strip constituting the source of supply to creep or work laterally towards the ring shaped member 4 on the carrier as the strip is fed off of and onto 50 the carrier. I also prefer to arrange a stationary sharp edged guiding device 11 at the upper side of the carrier B in close proximity to the inner side of the member 4 so as to force the strip away from said member 4 as 55 the strip is unwinding from the carrier.

An apparatus of the general construction and principle of operation above described can be used for handling various kinds of strips, either a strip having two ends or a 60 continuous strip. It is particularly adapted for use in a moving picture projecting machine, however, owing to the fact that it enables an endless film or picture strip of relatively great length to be confined in a 65 small space and run through the machine

time after time by simply continuing the film feeding mechanism in operation.

Having thus described my invention, what I claim as new and desire to secure by Letters Patent is:

1. The method of storing a flat record strip or film of flexible material having normally parallel edges of substantially equal length, which consists in winding the same upon a rotatable support with its flat faces 70 at a substantial angle to the axis of winding and forming it into coils in a series extending in the direction of the axis of winding and in condition to be unwound for reuse.

2. The method of receiving, storing, and returning for reuse a flat record strip or film of flexible material having normally parallel edges of substantially equal length which consists in winding the strip onto a 80 rotatable supporting member, and forming it into a helix with its coils in a series extending in the direction of the axis of winding, with the coils parallel to each other and disposed substantially at right angles 85 to the portion of the device onto which the strip is wound, and paying off the coils by unwinding from the end of the helix opposite to that at which they are wound on.

3. The method of storing record strips of 90 thin flexible material having normally parallel edges of substantially equal length, which consists in winding the strip edgewise upon a rotatable support, and forming it into a helix whose coils extend in series 100 in the direction of the axis of winding, and confining said coils in the direction of said axis with freedom of unwinding from said support.

4. The method of storing and paying out 105 for reuse a record strip of thin flexible material having normally parallel edges of substantially equal length, which consists in winding the strip edgewise about an axis of rotation, forming it into coils extending 110 in series in the direction of the axis of winding, and, after developing a helix of such coils, continuing the winding on at one end and simultaneous winding off at the other end of such helix.

5. The method of storing a flat flexible record strip having normally parallel edges of substantially equal length, characterized by feeding the strip to and winding it edgewise onto a rotatable device between confining portions on said device that maintain the strip against tipping and in a position substantially at right angles to the portion of the device on which the strip is wound.

6. The method of receiving, storing, and 125 paying out a flat transversely flexible strip of record film having normally parallel edges of substantially equal length, characterized by winding the strip edgewise into coils upon a rotatable device so as to form 130

a source of supply, maintaining the coils against tipping upon said rotatable device, and simultaneously feeding the strip off of said device; the coils of the strip being caused to move gradually in the direction of the axis of rotation of said device from the point of winding on to the point of feeding off.

7. The method of receiving, storing, and paying off a flat flexible strip of record film in the form of an endless belt or continuous band having normally parallel edges of substantially equal length, characterized by confining the main body of film in the form of a helix of coils wound edgewise in a series extending in the direction of the axis of the helix, and simultaneously feeding the film

off of and onto said helix at opposite ends thereof.

8. The method of handling, in the form of a continuous band, a flat flexible strip having sides substantially parallel and of equal length, characterized by winding the major portion of said strip on a rotatable supporting device in such a manner that the coils of the strip are arranged parallel to each other and at an angle to the axis of rotation of said device, and feeding the strip off of said device, to or through a means that acts on the strip or with which the strip cooperates and then back to said supporting device.

JOHN A. DE VILBISS.
